Primary Examiner—Nelson C. Holtje*Attorney, Agent, or Firm*—Renner, Kenner, Greive, Bobak, Taylor & Weber[57] **CLAIM**

The ornamental design for a sled panel, as shown and described.

DESCRIPTION

FIG. 1 is a top, right, front perspective view of a sled panel showing my new design;

FIG. 2 is a top plan view thereof;

FIG. 3 is a bottom plan view thereof;

FIG. 4 is a left side elevational view thereof, the right side being a mirror image of FIG. 4;

FIG. 5 is a front elevational view thereof; and,

FIG. 6 is a rear elevational view thereof.

The broken-line showings are environmental only and form no part of the claimed design;
